INVENTOR

UNITED STATES PATENT OFFICE.

GÜNTHER PHILIP WILD, OF PHILADELPHIA, PENNSYLVANIA, ASSIGNOR TO
FREDERICK W. SCHMIDT, OF PHILADELPHIA, PENNSYLVANIA.

THERMOSTAT.

1,013,854.

Specification of Letters Patent.

Patented Jan. 2, 1912.

Application filed December 7, 1910. Serial No. 596,056.

To all whom it may concern:

Be it known that I, GÜNTHER PHILIP WILD, a citizen of the United States, residing in the city and county of Philadelphia, State of Pennsylvania, have invented a new and useful Thermostat, of which the following is a specification.

My invention consists of certain improvements in a thermostat particularly adapted for use in a controlling apparatus for charging storage batteries, such as disclosed in Patents Nos. 976,748 and 976,750, granted to Frederick W. Schmidt, on the 22nd day of November, 1910.

It further consists of a thermostat capable of functions and possessed of properties similar to those performed and possessed by the thermostats for which Letters Patent, Nos. 976,747 and 976,749, were granted to Frederick W. Schmidt, on the 22nd day of November, 1910.

It further consists of a thermostat embodying the feature of an acid-resisting casing having a part of its outer surface electrically non-conductive and a part of such surface insulated or electrically conductive and exposed to the battery solution and electrically connected to one contact of the thermostat, such as disclosed and claimed in my co-pending application, Serial No. 595,284, filed on the 2nd day of December, 1910, for a thermostat.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it will be understood that the various instrumentalities of which my invention consists can be variously arranged and organized and that my invention is not limited to the precise arrangement and organization of these instrumentalities as herein shown and described.

Figure 1 represents a longitudinal sec-

tion of a thermostat, illustrating one embodiment of my invention. Fig. 2 represents a longitudinal section of a thermostat, illustrating another embodiment of my invention. Fig. 3 represents a longitudinal section of a thermostat, illustrating still another embodiment of my invention.

The thermostat has a metallic base-plate, 1, usually of brass, having a short post, 2, at one end, into which one end of a composite metal thermostat-bar, 3, is secured. The free end of said bar has a contact-point, 4, preferably of a metal fusible at a high temperature, only, which registers and may have contact, when the bar is flexed owing to the difference in the co-efficients of expansion of the two metals from which the bar is formed, with a contact point, 5, of the same metal and secured to the end of a contact-screw, 6, threaded, to be adjusted with its point nearer to or farther from the contact-point of the thermostat-bar in a yoke or bracket, 7, secured upon but insulated from the base-plate. The base-plate and thermostat are inclosed in the body, 8, of a casing, preferably of rectangular form, and having a cover, 9, secured liquid-tight to the upper edges of the side-walls.

In the forms illustrated in Figs. 1 and 2, the casing is formed from an electrically conductive but non-acid-resisting material, and the entire casing of the form illustrated in Fig. 1 is covered by a coating or envelop, 10, of porcelain, enamel, lacquer, or any suitable insulating or non-conductive material. Plugs or inserts, 11, of conductive and acid-resisting material, are inserted through the bottom of the casing and in electrical contact with the same and with the base-plate, and the outer surfaces of such inserts are not covered by the insulating coating but are exposed to the battery solution to form electrodes. The envelop and plugs or inserts form a part of the casing, being intimately united with the casing, proper, whereby the exposed surface of the same becomes wholly acid-resisting and in part electrically conductive, at the points where the envelop does not cover,

and the electrically conductive portion of the casing structure is electrically connected to one contact of the thermostat.

In the form illustrated in Fig. 2, the top 5 of the non-acid-resisting casing is covered by a coating, 12, of porcelain, enamel, lacquer, or any suitable insulating or non-conductive material, and the body of the casing is intimately covered by plating or 10 other process by a deposit, 13, of electrically conductive and acid-resisting material forming an electrode. A plate, 14, of acid-resisting and electrically non-conductive material, is secured to the outer surface of 15 the casing to cover the bottom thereof. As the non-conductive coating for the top, the plated deposit and the bottom plate are all intimately united with the casing, proper, all become portions of the inclosing casting-structure which will thus have an exposed surface which is wholly acid-resisting, 20 in part electrically conductive, at the uncoated sides, and electrically connected to one contact of the thermostat.

In the form illustrated in Fig. 3, the walls 25 of the casing, or as much of them as is exposed to the battery solution, are formed from acid-resisting and electrically conductive material, and the entire casing is covered by a coating or envelop, 15, of insulating or non-conductive and acid-resisting material, such as porcelain, enamel, lacquer or suitable insulating material, which envelop is formed with a number of openings, 16, 30 providing for contact by the conductive and acid-resisting exposed parts or electrodes of the casing with the battery solution.

Like in the two above referred-to forms, the envelop is intimately united with the 40 casing, proper, the whole thus forming a casing, the exposed surface of which is wholly acid-resisting and in part electrically conductive, at the points not covered by the intimate envelop, and electrically connected 45 to one contact of the electrode.

In all forms, the uncoated parts admit of the casing forming an electrode connected to one contact of the thermostat.

The cover of the casing in all of the forms 50 has a neck, 17, the upper face of which has annular ribs, 18. A binding-screw, 19, extends through the neck and has a flange, 20, upon it and having annular ribs, 21, upon its under side. A nut, 22, fits upon the screw 55 and serves as a binding-nut in conjunction with the flange. A tube, 23, of mica, insulates the screw from the opening in the neck, and a domed shield or washer, 24, fits upon this insulating tube and has annular corrugations, 25, surrounding its central opening. Gaskets, 26, of rubber or similar yielding material, and having a washer, 27, of mica, are interposed between the ribbed under-

side of the flange upon the screw and the upper corrugated face of the shield, and similar gaskets, 28, and interposed washer, 29, are held between the corrugated under-side of the shield and the annularly ribbed seat upon the neck. An insulating washer, 30, of mica, and a metallic washer, 31, are clamped against the under-side of the cover by a nut, 32, upon the lower portion of the binding-screw, which nut draws the gaskets and washers together to form a liquid-tight and insulated joint between the screw and the casing. A wire, 33, or similar conductor is attached to the lower end of the binding-screw and to the contact-screw of the thermostat. The casing is filled with a filling, 34, of an insulating and heat-conducting liquid, such as oil or similar liquid hydro-carbon, by means of which the elements within the casing are properly insulated, arcs formed between the contact-points will be extinguished, and heat will be conveyed 85 from the exterior of the casing to the thermostat bar.

Having thus described my invention, what I claim as new and desire to secure by Letters Patent, is:—

1. A thermostat, a concrete and unitary casing for the same formed from electrically conductive material and electrically connected to one contact of the thermostat and having portions of its outer surface rendered non-conductive by an electrically non-conducting and acid-resisting coating and the noncoated portions of the conductive material being acid-resisting.

2. A thermostat, a concrete and unitary 100 casing for the same formed from electrically conductive material and having the greater part of its outer surface rendered non-conductive by an electrically non-conducting and acid-resisting coating, and an acid-resisting electrode electrically connected to one 105 element of the thermostat and uncovered by said coating.

3. A thermostat, a concrete and unitary 110 casing for the same having its outer surface wholly acid-resisting and having parts of such surface electrically non-conductive and parts of the same electrically conductive and electrically connected to one element of the thermostat.

4. A thermostat, a concrete and unitary casing for the same having its outer surface wholly acid-resisting and the greater part thereof electrically non-conductive and a part of the same electrically conductive to 115 form an electrode connected to one of the elements of the thermostat.

5. A thermostat, a concrete and unitary casing for the same forming an electrode electrically connected to one element of the 120 thermostat and having its outer surface

- wholly acid-resisting and the greater part thereof electrically non-conductive and having a portion exposed through the non-conductive surface.
- 5 6. A thermostat, a concrete and unitary casing for the same having its outer exposed surface acid-resisting and electrically non-conductive and formed with acid-resisting and electrically conductive inserts forming parts of the walls of the casing and electrically connected to one element of the thermostat and extending to be exposed through the non-conductive surface of the casing. 10
